UNITED STATES PATENT OFFICE.

CARL LINDAHL, OF NEWARK, NEW JERSEY, ASSIGNOR TO AMERICAN GAS ACCUMULATOR COMPANY, OF ELIZABETH, NEW JERSEY, A CORPORATION OF NEW JERSEY.

FLASHER.

Application filed April 30, 1925. Serial No. 27,120.

My invention relates to a fluid actuated device for permitting an intermittent flow of fluid such as gas and is particularly adapted for embodiment in what may be termed a 5 flasher for use in lighthouses, buoys or towers on air routes and the like.

Heretofore flashers have been developed which depended upon magnetic devices for effecting the proper operation thereof.

10 It is an object of my invention to provide a flasher of novel construction in which the gas or other fluid, which is afterward consumed, actuates the mechanism for effecting intermittent flashes.

15 It is another object to provide a flasher in which a valve and fluid actuated means are mechanically and adjustably connected by novel means.

It is still another object to provide a valve 20 which when open will be partially or substantially balanced so far as fluid pressure is concerned.

It is a further object to provide improved means for throttling a flow of fluid and at 25 the same time filtering out foreign matter.

It is another object to improve certain combinations and mechanical details of construction in a flasher.

Briefly stated, in the preferred form of the 30 invention embodied in a gas flasher, I employ a chamber into which gas under suitable pressure is conducted. There is a valve for controlling the distribution of gas to a gas consuming device such as a burner. A diaphragm or the like is movable under the influence of the fluid pressure in the fluid chamber. Means is interposed between said diaphragm and the said valve which, upon movement of said diaphragm under fluid 35 pressure, is adapted to cause movement of said valve. The said means may be adjustable so as to vary the time of actuation of the valve and thus vary the period between the flashes. When the device is used as a gas 40 flasher a constantly burning pilot light is preferably employed for igniting the gas flowing at intervals to the burner.

In the drawing I have shown for illustrative purposes only, a preferred form of the 45 invention, which drawing illustrates a substantially central sectional view of a gas flasher. In the drawing:

1 indicates a gas chamber into which gas is conducted from an inlet connection 2, 50 which in turn is connected to a source of gas

supply preferably including a reducing valve (not shown) for supplying the gas at the desired pressure. 3 indicates a valve block provided with a valve chamber 4. The block 3 is supported upon and in spaced relation to the main body block 5 by means of a spider member 6. The block 3 is secured, preferably detachably, to the spider 6 by means of screws 7—7. This construction permits a ready removal of the valve block 3 in case it 60 becomes necessary to repair or renew the same. 8 indicates what may be termed a burner head which may be secured to the block 3.

In the form shown, one side of the chamber 1 is closed by means such as the diaphragm 9, which may be secured between the lower end of the spider 6 and the main body block 5, so as to form a gas tight connection. A spring or the like 10 serves to urge the diaphragm 9 toward the collapsed position. A tubular sleeve 11 is fixedly secured to the diaphragm 9 by means of a nut 12 and a spring abutment 13 may be threaded or otherwise adjustably secured on the upstanding sleeve 11. A stem 14 may be slidably housed and guided in the sleeve 11 and in order to permit a restricted telescopic movement between the stem 14 and sleeve 11, the latter may be slotted as at 15 to receive a pin 85 or key 16 carried by the lower end of the stem 14. It will thus be seen that the sleeve and stem may move relatively to each other to a slight extent but accidental removal of the stem from the sleeve will be prevented. 90 A second spring abutment 17 may be threaded or otherwise adjustably secured on the stem 14 and a spring 18 may be interposed between the abutments 13 and 17 so as to normally urge the parts 11 and 14 into extended 95 position.

The valve block 3 may have a sealing member such as the diaphragm 19 secured thereto as by means of a nut 20 which may be apertured to receive and guide the upper end 21' 100 of the stem 14. The valve block has a gas passage 21 connecting the gas chamber 4 with the pipe 22 or other connection leading to the jet as will be later described, and it is for sealing this passage that the diaphragm 19 is employed.

In the preferred form the valve 23 when closed rests upon an annular seat 25 and the pressure is above the valve and thus normally tends to maintain the same in 110

closed position. The outlet for the fluid beneath the valve is preferably restricted so that the flow through the outlet 21 must be at a slower rate than that at which the fluid 5 may pass between the seat 25 and the valve so that when the latter is unseated the fluid pressure on the valve will be partially and in some cases substantially balanced. As one means of providing such a restricted 10 outlet I may employ a second inner and concentric valve seat 26 in the chamber 4 and it will be evident that when the valve is in open position, fluid under pressure may enter between the seat 25 and the valve at a 15 much greater rate than it may pass between the valve and the inner seat 26. A spring or the like may be positioned above the valve 23 for urging the same toward the closed position.

20 In the gas inlet passage to the chamber 1, I preferably form an enlargement which if desired may be formed directly in the base member 5. In this enlargement or chamber is packed a quantity of fibrous material such as asbestos wool 30. This asbestos wool serves to throttle the passage of gas from the pipe 2 into the chamber 1 and also serves to remove foreign matter such as dust and the like which may sometimes come 25 over with the gas from a gas container. In order to further control the flow of gas into the chamber 1, I may employ a needle valve 31 or the like which may be moved in either direction by means of a knurled nut 32. 30 When the needle valve 31 is moved inwardly, the fibrous material is compressed so that the interstices are reduced in size and the flow of gas consequently throttled. A pipe 33 preferably connected to the same source 35 of supply as that connected to the pipe 2 conducts gas to the passage 34 in the burner block 8 and in this block I preferably provide a similar form of gas filtering and throttling device as that just described. As 40 shown in the burner block, there is a quantity of fibrous material 35 seated in an enlargement of the passage 34. This gas from pipe 33 after passing through the fibrous material enters a pipe 36 which is connected 45 to a pilot burner (not shown) and furnishes a continuous supply of gas thereto.

The operation of the device is as follows:

50 Gas under the desired pressure is conducted through the pipe 2 and through the fibrous material 30 and into the chamber 1 where the pressure builds up and raises or expands the diaphragm 9. When the diaphragm is raised to such an extent that the upper end 37 of the sleeve 11 engages the 55 abutment 17 on the stem 14 (the spring 18 during this operation being compressed), the upper end 21' of the stem acts through the sealing diaphragm 19 to engage the valve stem 24 and raise the latter against the pressure of the spring 27 and the fluid pressure

acting above the valve 23. As soon as the valve 23 is raised slightly, gas flows between the valve and the outer annular seat 25 at a relatively rapid rate and the pressure thereunderneath said valve at least partially 70 balances the pressure on the opposite side thereof. As soon as the fluid pressure is partly balanced, the spring 18 which was previously compressed overcomes the pressure of the spring 27 and throws the valve 75 23 to open position with a snap action. Now with the valve open, the accumulated gas from the chamber 1 flows through the connecting pipe 38 into the valve chamber 4, then beneath the valve past the inner valve 80 seat 26 down through the passage 21, then through pipe 22 to passage 39 which is connected to any suitable type of gas burner 40 on the block 8. As the pilot light is always burning the gas flowing through the 85 passage 39 to the jet 40 will be ignited so as to give a flash.

The various passages are so proportioned that the gas is consumed at a greater rate than it is permitted to enter the chamber 1 through the pipe 2. It will thus be evident that the gas pressure in the chamber 1 gradually diminishes and as it diminishes the spring 27 and the gas pressure acting above the valve 23 and the spring 10 acting above the diaphragm causes the latter to be forced inwardly or to collapsed position.

90 When the valve 23 is closed the spring 27 and whatever fluid pressure may be in the chamber 4 maintains the valve in closed position until it is again actuated as previously described.

95 It will be obvious that if there was a rigid connection at all times between the valve stem 24 and the diaphragm 9 that each very slight increase in pressure would raise the valve and there would be a succession of very brief flashes or flickers; in other words, there would be what might be termed a chattering of the valve.

100 It will be equally plain that if the valve is actuated by the diaphragm only when the upper end 37 on the sleeve 11 engages the spring abutment 17, the farther apart the parts 37 and 17 are positioned, the less frequent will be the actuation of the valve. I have, therefore, shown the abutment 17 as being adjustably mounted along the stem 14 so that it may be positioned at any practicable distance from the end 37 of the sleeve 115 so as to vary the number of flashes per unit of time between any desired practicable limits.

110 While the invention has been described in great detail and a preferred form illustrated as embodied in a gas flasher, I do not wish to be limited to the form shown since changes may be made within the scope of the invention as defined in the appended claims and certain features herein disclosed may be used 125 120 130

to advantage in connections other than here illustrated.

I claim:

1. In a device of the character described, a member provided with a fluid chamber, a diaphragm movable under the influence of fluid in said chamber, a fluid consuming device, a valve to control the flow of fluid from said chamber to said fluid consuming device, means for connecting said valve and said diaphragm for moving said valve in one direction, said means including a pair of telescopic members and an abutment on one of said members to be engaged by said other member when said diaphragm is moved by fluid in said chamber to move said valve.
2. The combination defined in claim 1, and means for moving said valve with a snap action when the movement thereof has been initiated by said diaphragm and telescopic connection.
3. In a device of the character described, a member provided with a fluid chamber and having an inlet through which fluid enters said chamber, a fluid consuming device, a passage connecting said fluid chamber and said fluid consuming device, a valve of relatively large area for controlling communication through said passage, said valve when closed being held to its seat partially by fluid pressure in said fluid chamber, and means connecting said diaphragm and valve whereby when the pressure in said fluid chamber increases, said valve will be moved off its seat so as to open communication between said chamber and said fluid consuming device.
4. The combination defined in claim 3 and resilient means for causing said valve to move away from its seat with a snap action.
5. The combination defined in claim 3 and resilient means for urging said valve toward its seat.
6. In a device of the character described, a member provided with a fluid chamber, a diaphragm extending across said chamber and adapted to be expanded by the pressure of fluid in said chamber, a fluid consuming device, means including a passageway for conducting fluid from said chamber to said fluid consuming device, a valve for controlling the said passageway, a spring constantly urging said valve toward its seat, and means interposed between the said diaphragm and the said valve and including a resilient member for causing initial opening movement of said valve upon expansive movement of said diaphragm which resilient member is adapted to be placed under compressive tension by the expansive movement of said diaphragm and to effect quick further opening movement of said valve after the said initial opening movement thereof.
7. In a device of the character described, the combination of a member provided with a chamber adapted to receive a combustible gaseous fluid, a diaphragm extending across and closing said chamber, a burner, means including a passageway for conducting said fluid to said burner, a valve for controlling the passage of fluid through said passageway, a rod having connection at one end with said diaphragm and terminating at its other end in operative relation to the said valve, said rod being provided with an adjustable abutment in spaced relation to the said diaphragm, a tubular sleeve movably mounted upon said rod intermediate the said diaphragm and the abutment on said rod, the outer end of said sleeve normally terminating in spaced relation to the said abutment, and the said sleeve being also provided with an adjustable abutment, and a coiled spring surrounding the said sleeve and rod and contacting at its opposite ends with the said abutments and tending to separate the same, the expansive movement of the said diaphragm causing outward movement of the said sleeve to compress the said spring to cause initial opening movement of the said valve after which the said spring expands to cause a quick further opening movement thereof.
8. In a device of the character described, the combination of a member provided with a chamber adapted to receive a combustible fluid, a diaphragm extending across and closing said chamber, resilient means which tends to cause collapsing movement of the diaphragm, a burner, means including a passageway for conducting fluid from said chamber to said burner, the said passageway including an intermediate chamber of wide area, a valve of wide area located in said chamber, concentric seats for the said valve, the diameter of the inner seat being relatively small and that of the outer seat being relatively great, the said valve having a stem extending through a portion of the passageway substantially at right angles to the said diaphragm, said stem terminating in a chamber, a diaphragm extending across said chamber with which the end of the stem is in contact, a rod having connection with the said diaphragm and extending into the said last mentioned chamber in alignment with the stem of the said valve and being adapted to contact with the said last mentioned diaphragm, an adjustable abutment mounted on said rod in spaced relation to the first named diaphragm, a tubular sleeve movably mounted on said rod and connected with the said diaphragm, the outer end of said sleeve terminating normally in spaced relation to the said abutment, the said sleeve being also provided with an adjustable abutment, and a coiled spring located intermediate the said abutments which spring is adapted to be placed

under tension upon expansive movement of the first named diaphragm, which spring operates through the said rod and through the stem of the said valve to cause initial opening movement of the said valve and to thereafter cause quick further opening movement of the said valve.

9. In a device of the character described, the combination of a member provided with a combustible fluid receiving chamber, a diaphragm extending across and closing said chamber, a burner, means including a passageway for conducting fluid from said chamber to the said burner, the said passageway including a chamber of relatively wide transverse area, a portion of the said passageway leading from the bottom of said chamber, a valve of relatively wide area located in said last mentioned chamber and adapted to control the passage of fluid through said passageway, the pressure of fluid in the said last mentioned chamber tending to hold the said valve in closed position, seats for the said valve which are concentrically located with respect to each other, the diameter of the inner seat being relatively small as compared with the diameter of the outer seat whereby when initial opening movement of the said valve is effected the said fluid flows more rapidly underneath the said valve and past the outer seat therefor than it is permitted to flow past the inner seat, whereby the downward pressure of the fluid upon the said valve is partially counterbalanced by the fluid underneath the said valve, and means operating to cause initial opening movement of the said valve and to thereafter cause quick further opening movement thereof.

40. In a device of the character described, the combination of a member provided with a chamber adapted to receive a combustible gaseous fluid under pressure, a flexible diaphragm extending across said chamber, which diaphragm is adapted to expand and contract in accordance with the variation of pressure of the fluid in said chamber, a burner, means including a passageway for conducting said fluid to said burner, a valve for controlling the flow of gas through said passageway, and means interposed between the said passageway and the said valve for effecting first an initial opening movement of the said valve and for thereafter causing further quick opening movement of said valve.

11. In a device of the character described, a fluid chamber, a diaphragm under the influence of fluid pressure in said chamber, a spring for urging said diaphragm to a collapsed position, a valve chamber, means for conducting fluid from said fluid chamber to said valve chamber, a fluid consuming device, means for conducting fluid from said valve chamber to said fluid consuming device, a valve for controlling said last mentioned means, a spring for urging said valve toward its seat, means actuated by said diaphragm for moving said valve off of its seat, said means including a pair of telescopic members having a limited movement relatively to each other, a spring for urging said telescopic members apart, and abutment means on one of said telescopic members to be engaged by the other of said telescopic members whereby said spring between said telescopic members will be compressed when said diaphragm moves under the influence of fluid pressure and said telescopic members including said abutment, will positively raise said valve from its seat and thereafter said spring between said telescopic members will further move said valve with a snap action.

12. The combination as defined in claim 11, the said abutment being adjustable whereby the timing of the actuation of said valve by said diaphragm may be varied.

13. In a device of the character described, a member provided with a fluid chamber, a diaphragm extending across said chamber and adapted to be expanded by the pressure of fluid in said chamber, a fluid-consuming device, means including a passageway for conducting fluid from said chamber to said fluid-consuming device, a valve for controlling the said passageway, a spring constantly urging said valve toward its seat, means interposed between the said diaphragm and the said valve for causing initial opening movement of said valve upon expansive movement of said diaphragm, which means includes a resilient member which is adapted to be placed under compressive tension by the expansive movement of said diaphragm and to effect quick further opening movement of said valve after the said initial opening movement thereof, and a spring for urging said diaphragm in one direction.

CARL LINDAHL.
